UNITED STATES PATENT OFFICE.

ERIC HOLLOCOOMBE CLIFT, OF WEST KENSINGTON, ENGLAND.

INTERNAL-COMBUSTION ENGINE.

No. 873,840.

Specification of Letters Patent.

Patented Dec. 17, 1907.

Application filed March 25, 1907. Serial No. 364,556.

To all whom it may concern:

Be it known that I, ERIC HOLLOCOOMBE CLIFT, a subject of the King of Great Britain and Ireland, residing at 51 Sinclair road, 5 West Kensington, in the county of London, England, have invented a new and useful Improvement in Internal-Combustion Engines, of which the following is a specification.

10 This invention relates to internal combustion engines, and it consists in mounting the inlet and exhaust valves concentrically, the former being within the latter so that the hollow stem of the exhaust valve forms part 15 of the induction pipe and being hot acts as a vaporizer for the incoming charge and in providing means for regulating the temperature of said vaporizer.

In the accompanying drawing:—Figure 1, 20 Sheet No. 1, is a view in side elevation—partly in section—of one method of carrying the present invention into effect, Fig. 2 Sheet No. 2 is a view in plan showing the inlet and outlet to the jacket of the valve box and an 25 alternative construction of the clamping ring, and Fig. 3, Sheet No. 3, is a broken view in sectional elevation showing an alternative construction.

Throughout the views similar parts are 30 marked with like letters of reference.

The inlet valve *a* and the exhaust valve *b* are arranged concentrically with respect to one another, the inlet valve being within the exhaust valve the stem *b*¹ of which has a passage *a*⁴ through it. This stem is mounted in a detachable annular box *c* adapted to be fixed in the cylinder head *x* in any convenient manner, preferably by forming a seating *x*¹ within the cylinder head with which a 35 seating *c*¹ on the box *c* engages. The box is held in position by means of a clamping ring *y* which may either be formed with a tongue *y*² on one side and a forked or slotted part *y*³ on the opposite side as shown in Fig. 1 or 40 with a fork at each end as shown in Fig. 2. The tongue *y*² is adapted to engage a slot or recess *x*² formed in a bracket *x*³ carried by the cylinder head *x* and the slotted part *y*³ is engaged by a nut *y*⁴ on a stud *y*¹ fixed 45 in the cylinder head. This box is formed with an annular chamber *c*⁴ which forms an independent water jacket round the valves. This chamber has a suitable inlet *v* and outlet *w* provided with means, such as a stop 50 cock, whereby the flow of water through the said chamber can be regulated so as to vary 55

the temperature in the vaporizer. In the cylinder head *x* and valve box *c* are openings *x*⁶ and *c*⁶ through which a lamp or other means of initially heating the vaporizer can be introduced for starting when heavy oils are employed. Similar openings *x*² and *c*² are provided for the escape of the exhaust gases. In the hollow stem *b*¹ of the exhaust valve *b* are mounted perforated guides *a*¹ *a*² for the 60 stem *a*³ of the inlet valve *a*. The external diameter of the stem *a*³ of the inlet valve and the internal diameter of the hollow stem *b*¹ of the exhaust valve are such that there is an annular passage or chamber *a*⁴ between 65 the stem of the inlet valve and the inner wall of the hollow stem of the exhaust valve which forms a vaporizer which is in communication with the fuel supply by means of the pipe *a*⁵ which is a sliding fit in the hollow 70 stem *b*¹ of the exhaust valve. In the part of this annular passage or chamber between the guides *a*¹ and *a*² are placed a series of metal balls *d* or their equivalents which operate to 75 thoroughly break up and atomize the incoming charge as being loosely packed in the chamber they are moved or agitated each time the valves open and close.

In some cases provision may be made for further agitating or imparting movement to 80 the balls by forming ridges or recesses *r* on or in the stems of one or both of the valves.

The inlet valve may be operated either atmospherically, or mechanically, by means of a screw *v*¹ carried by a rocking lever *v* as 85 shown. The inlet valve *a* is controlled by the spring *a*⁶ located within the upper end of the passage or chamber *a*⁴ through the stem of the exhaust valve and taking a bearing on the upper side of the guide *a*².

The exhaust valve *b* is controlled by the spring *b*² and is operated by a rocking lever *v*², the forked end of which contacts a flange *v*³ on the stem *b*¹ of the valve.

It will be seen that with a multiple cylinder engine embodying the herein described improvement access may be readily obtained to the interior of any one of the cylinders, or any one of the valve boxes may be removed while the engine is running, which construction is particularly useful for marine purposes.

What I claim as my invention and desire to secure by Letters Patent is:—

1. In an internal combustion engine, the 110 combination of an exhaust valve having an enlarged stem with a centrally arranged pas-

- sage through it forming an induction pipe, a
5 detachable box having a seating for said
valve, an inlet valve for closing the passage
through the exhaust valve the stem of the
said valve being of a smaller diameter than
10 the bore of the stem of the exhaust valve,
guides in the hollow stem of the exhaust
valve for the stem of the inlet valve, a seat-
ing for said inlet valve in the head of the ex-
haust valve, a water jacket in the detach-
15 able box carrying the seating for the exhaust
valve and surrounding the guide for said
valve, a feed supply pipe fitting within the
end of the hollow stem of the exhaust valve,
springs operating to retain the valves on
20 their respective seatings, and means for op-
erating the said valves to open them by re-
moving them from their seatings, as set
forth.
- 20 2. In an internal combustion engine, the
combination of an exhaust valve having an
enlarged stem with a centrally arranged pas-
sage through it forming an induction pipe, a
25 detachable box having a seating for said
valve, an inlet valve for closing the passage
through the exhaust valve the stem of the
said valve being of a smaller diameter than
30 the bore of the stem of the exhaust valve,
guides in the hollow stem of the exhaust
valve for the stem of the inlet valve, a seat-
ing for said inlet valve in the head of the ex-
haust valve, a water jacket in the detach-
35 able box carrying the seating for the exhaust
valve and surrounding the guide for the said
valve, a feed supply pipe fitting within the
end of the hollow stem of the exhaust valve,
springs operating to retain the valves on
40 their respective seatings, and means for op-
erating the said valves to open them by re-
moving them from their seatings, as set
forth.
3. In an internal combustion engine, the
combination of an exhaust valve having an
enlarged stem with a centrally arranged pas-
45 sage through it forming an induction pipe,
a detachable box having a seating for said
valve, an inlet valve for closing the passage
through the exhaust valve the stem of the said
50 valve being of a smaller diameter than the
bore of the stem of the exhaust valve, guides
in the hollow stem of the exhaust valve for
the stem of the inlet valve, a seating for said
inlet valve in the head of the exhaust valve,
55 a water jacket in the detachable box carrying
the seating for the exhaust valve and sur-
rounding the guide for said valve, a series of
metal balls or spheres in the annular chamber
60 in the hollow stem of the exhaust valve be-
tween the guides therein, a feed supply pipe
fitting within the end of the hollow stem of
the exhaust valve, springs operating to re-
tain the valves on their respective seatings,
65 and means for operating the said valves to
open them by removing them from their
seatings as set forth.
4. In an internal combustion engine, the
combination of an exhaust valve having an
enlarged stem with a centrally arranged pas-
sage through it forming an induction pipe, a
70 detachable box having a seating for said
valve, an inlet valve for closing the passage
through the exhaust valve the stem of the
said valve being of a smaller diameter than
75 the bore of the stem of the exhaust valve,
guides in the hollow stem of the exhaust
valve for the stem of the inlet valve, a seat-
ing for said inlet valve in the head of the ex-
haust valve, a water jacket in the detach-
80 able box carrying the seating for the exhaust
valve and surrounding the guide for said
valve, means for regulating the flow of water
through said jacket, a series of metal balls
or spheres in the annular chamber in the
85 hollow stem of the exhaust valve between
the guides therein, a feed supply pipe fitting
within the end of the hollow stem of the ex-
haust valve, springs operating to retain the
valves on their respective seatings, and
90 means for operating the said valves to open
them by removing them from their seatings,
as set forth.
5. In an internal combustion engine, the
combination of an exhaust valve having an
enlarged stem with a centrally arranged pas-
95 sage through it forming an induction pipe, a
detachable box having a seating for said
valve, an inlet valve for closing the passage
through the exhaust valve the stem of the
100 said valve being of a smaller diameter than
the bore of the stem of the exhaust valve and
extending completely through said hollow
stem, guides in the hollow stem of the ex-
haust valve for the stem of the inlet valve, a
105 seating for said inlet valve in the head of the
exhaust valve, a water jacket in the detach-
able box carrying the seating for the exhaust
valve and surrounding the guide for said
valve, a series of metal balls or spheres in
110 the annular chamber in the hollow stem of the
exhaust valve between the guides therein,
ridges or recesses on or in the stem of the in-
let valve, a feed supply pipe fitting within
the end of the hollow stem of the exhaust
115 valve, springs operating to retain the valves
on their respective seatings, and means for
operating the said valves to open them by re-
moving them from their seatings, as set
forth.
6. In an internal combustion engine, the
combination of an exhaust valve having an
enlarged stem with a centrally arranged pas-
120 sage through it forming an induction pipe, a
detachable box having a seating for said
valve, an inlet valve for closing the passage
through the exhaust valve the stem of the
125 said valve being of a smaller diameter than
the bore of the stem of the exhaust valve and
extending completely through said hollow
stem, guides in the hollow stem of the ex-
haust valve for the stem of the inlet valve, a
130

seating for said inlet valve in the head of the exhaust valve, a water jacket in the detachable box carrying the seating for the exhaust valve and surrounding the guide for said valve, a series of metal balls or spheres in the annular chamber in the hollow stem of the exhaust valve between the guides therein, ridges or recesses on or in the stem of the inlet valve, a feed supply pipe fitting within the end of the hollow stem of the exhaust valve, springs operating to retain the valves on their respective seatings, and means for operating the said valves to open them by removing them from their seatings, as set forth.

7. In an internal combustion engine, the combination of an exhaust valve having an enlarged stem with a centrally arranged passage through it forming an induction pipe, a detachable box having a seating for said valve, an inlet valve for closing the passage through the exhaust valve the stem of the said valve being of a smaller diameter than the passage through the stem of the exhaust valve and extending completely through said hollow stem, guides in the hollow stem of the exhaust valve for the stem of the inlet valve, a seating for said inlet valve in the head of the exhaust valve, a series of metal balls or spheres in the annular chamber in the hollow stem of the exhaust valve between the guides therein, a feed supply pipe fitting within the end of the hollow stem of the exhaust valve, springs operating to retain the valves on their respective seatings, and means for operating the said valves to open them by removing them from their seatings, as set forth.

8. In an internal combustion engine, the combination of an exhaust valve having an enlarged stem with a centrally arranged passage through it forming an induction pipe, a detachable box having a seating for said valve, an inlet valve for closing the passage

through the exhaust valve the stem of the said valve being of a smaller diameter than the passage through the stem of the exhaust valve and extending completely through said hollow stem, guides in the hollow stem of the exhaust valve for the stem of the inlet valve, a seating for said inlet valve in the head of the exhaust valve, a series of metal balls or spheres in the annular chamber in the hollow stem of the exhaust valve between the guides therein, ridges or recesses on or in the stem of the inlet valve, a feed supply pipe fitting within the end of the hollow stem of the exhaust valve, springs operating to retain the valves on their respective seatings, and means for operating the said valves to open them by removing them from their seatings, as set forth.

9. In an internal combustion engine, the combination of an exhaust valve having a hollow stem, a detachable seating for said valve, an inlet valve having a stem passing through the hollow stem of the exhaust valve the exterior diameter of which is less than the internal diameter of the stem of the exhaust valve so as to leave an annular chamber within the stem of the exhaust valve which forms a vaporizer, a seating for said inlet valve in the head of the exhaust valve, a series of metal balls or spheres in the annular chamber within the stem of the exhaust valve, a connection between the feed supply pipe and the hollow stem of the exhaust valves, springs operating to retain said valves on their respective seatings, and means for operating the said valves to open them by removing them from their seatings as set forth.
